INVENTOR.

John H. Kinter,
By L. Deane his Am't.

UNITED STATES PATENT OFFICE.

JOHN H. KINTER, OF INDIANA, PENNSYLVANIA.

GATE.

SPECIFICATION forming part of Letters Patent No. 320,257, dated June 16, 1885.

Application filed October 31, 1884. (No model.)

To all whom it may concern:

Be it known that I, JOHN H. KINTER, a citizen of the United States, residing at Indiana, in the county of Indiana and State of Pennsylvania, have invented certain new and useful Improvements in Gates, of which the following is a specification, reference being had therein to the accompanying drawings.

Figure 1 is a perspective view of the gate, 10 the dotted lines indicating the vertical movement of its panel. Fig. 2 is a perspective view in detail of the gate-slide. Fig. 3 is a detail view of sill. Fig. 4 is a detail view of the post A', showing slide H.

15 This invention relates to farm-gates and to gates generally wherein it is desired to swing a gate in such manner that it can be elevated or placed at any desired height or position.

The object of this invention is practically 20 to suspend a gate or door on strong link or other hinges substantially without the use of a heavy chain, and adjustably, so that it can be conveniently elevated or turned down to allow it to pass over obstructions; also, to allow the herdsman to separate small stock; also, 25 to swing a gate or door level, or as desired, on a sagged post, or for other reasons.

In the drawings hereto annexed, A designates the gate-post to which the gate is hinged. 30 A' designates the post to which the gate is fastened when shut. The gate proper may be of any suitable form or construction.

The panel B, as shown in the drawings, is made of the horizontal rails b and front and 35 end parts, b' b'', each formed of vertical parallel pieces or strips, the ends of the middle rails being confined between these pieces. At the end of this panel and between it and the post A is the part b'', made in like manner as b' b''. 40 C C designate one part of the hinges of the gate, and are practically staple-bolts, which are passed through and secured to the post A and provided with one or more washers or blocks, e'. To the eyes of these bolts are linked 45 or hooked the metal rods D D, which pass between the two parts which make up the rear part, b', of the gate, and through the face-plate E and clasps d d', and are provided with nuts e' e' on their screw-threaded ends. These clasps 50 are pieces of metal with bent ends, and so made that they fit upon the edges of the vertical end part b'. If desired, a like clasp, d'', can be placed on the other end of the rods so as to fit in like manner upon the other face of 55 the end part b'. The face-plate E, slotted at

e nearly from top to bottom, comes between the clasps d d' and the inner edge of b'', and, among other uses, serves as a metallic bearing for said clasps.

It will be observed that the gate is readily 60 adjustable vertically by loosening the nuts e' e', and it will also be seen that the slotted face-plate and the clasps, together with the nuts, permit the gate-panel to be firmly secured to the eyebolts, which constitute the hinges of 65 the gate proper.

The latch end of the gate is raised or lowered, as desired, by the addition or detraction of the blocks or washers e' on the lower hinge on post A. The gate will turn horizontally or 70 can be reversed by removing the upper clasp and the upper rod, D, and the gate will then be supported on the lower hinge, and can then be turned as desired.

At the bottom of the hinged end a block, a, 75 is fixed near the post A, with a screw-pivot, a'. In lowering a heavy gate a board is placed on the block as high as the pivot to receive the weight of the gate. If the drop should be more sudden than desired, this will protect the 80 hinges.

The latch end is supported and fastened by bolt j at any required height by means of the slotted piece H, adjustably fixed on the face of post A by bolts and nuts k k' k''. This construction will also hold the gate pivotally at any desired position when turned down.

Having described my invention, I claim—

1. The combination, in a vertically-adjustable horizontally-swinging gate, of the panels 90 b' b'', the eyebolt-hinges, the slotted face-plate E, the clasps d d' d'', and the nuts, substantially as described.

2. The combination, with the gate and its posts, of the eyebolt-hinges, their clasps and 95 nuts, the slotted plate E, the screw-pivot a', the slotted plate H, and the fastening-bolt, substantially as described.

3. In a gate, the combination of the panels b' b'', with the hinge, the slotted face-plate E, the clasps d and d', and retaining-nuts, whereby said gate is vertically adjustable, substantially as and for the purposes set forth.

In testimony whereof I affix my signature in presence of two witnesses.

JOHN H. KINTER.

Witnesses:

P. D. FISCUS,
J. H. SMITH.
